UNITED STATES PATENT OFFICE.

JOHN H. WAIT, OF PORTSMOUTH, OHIO.

IMPROVEMENT IN BALANCE SLIDE-VALVES.

Specification forming part of Letters Patent No. 58,699, dated October 9, 1866.

To all whom it may concern:

Be it known that I, JOHN H. WAIT, of Portsmouth, in the county of Scioto and State of Ohio, have invented a new and useful Improvement in Balance Slide-Valves; and I do hereby declare the following to be a full, clear, and exact description of the same, reference being had to the accompanying drawings, which are made a part of this specification, and in which—

Figure 1 is a vertical longitudinal section of a steam-cylinder with my improved valve applied. Fig. 2 is a horizontal section of the same, the line $x-x$, Fig. 1, indicating the plane of section. Fig. 3 is a detail view, showing the inner face of one of the valves in elevation.

Similar letters of reference indicate corresponding parts in the several figures.

This invention relates to a slide-valve for regulating the supply and exhaust of steam in a steam-cylinder, and consists in a valve-block mounted upon and communicating with the steam-channels on top of the cylinder, and provided on either side with a reciprocating valve having steam passages or channels, which are alternately brought into communication with the supply and exhaust ports of the valve-block.

In order that others skilled in the art to which my invention appertains may be enabled to fully understand and use the same, I will proceed to describe it in connection with the accompanying drawings.

A represents the block or main body of the valve, which occupies a fixed position midway between the ends of the cylinder B and communicates with the latter through the steam-channel C C'. D D represents slide-valves working at the opposite sides of the valve-block A, and reciprocated simultaneously in the same direction by the valve-rod E.

F represents the steam-supply port, and G G the exhaust-ports. In Fig. 2 the dotted circles designate the position of these ports, and in this figure will also be more clearly seen the arrangement of said ports in relation to the steam-passages d^1 d^1 d^2 of valves D D and a^1 a^1 a^2 a^3 a^4 of valve-block A.

The valves D D are connected together by the bolts H H and nuts I I, and are thereby held sufficiently tight against the valve-block A to prevent the waste of steam. The bolts

H H at the ends of the valve are provided with rollers J J, which traverse guideways at b b , and serve to relieve the bearings of the valve from friction.

The operation of this valve may be briefly stated, and will be readily understood.

The steam-channels C C' alternately become the supply and exhaust passages for the steam-cylinder, for which purpose the passages a^1 a^3 of the valve-block A are in constant communication with the steam-channels C C', the passages a^1 a^4 are in constant communication with the exhaust-ports G G, and the central passage, a^2 , of the valve-block A is always in communication with the supply-port F. When C becomes the steam-supply channel and C' the exhaust-channel the relation between the several passages in the valves D D, valve-block A, and steam and exhaust ports is as represented in Fig. 2—that is to say, the central passages, d^1 d^1 , of the valves D D are in communication with the supply-port F, central supply-passage, a^2 , and passage a^1 , and steam passes through these passages down into the steam-channel C, as represented by the arrows in Figs. 1 and 2, and while communication between the passages a^1 and d^1 is closed it is open between the corresponding passages a^3 and d^2 d^2 , and the steam is permitted to pass from the channel C' through the passages a^3 , d^2 , and a^4 , and exhaust-port G. When the position of the valves D D is reversed their central passages, d^1 d^1 , open communication between the central supply-passage, a^2 , and passage a^3 , when steam is supplied through channel C' and exhausted through channel C, the course of the steam through the several passages and ports being just the reverse of that which is traced in the preceding paragraph.

The grooves e (represented in Fig. 3, and designated by the red lines in Fig. 2) are formed in the valves D D to receive and conduct into the exhaust-ports any steam which may work its way into the joints between the valves and valve-block. Hence the steam which would escape under the various adjustments of the several parts induced by unequal temperature is, by the grooves, directed into the ports, and prevented from making its appearance around the outside of the valve.

It will be seen that under this arrangement the pressure of the steam upon one of the valves D is counteracted by the pressure upon the opposite valve; hence they are strictly balanced, there being no friction upon the bearings or contiguous faces in consequence of the action of the steam.

It is evident that the number and arrangement of the passages may be varied without departing from the essential feature of the invention.

Having thus described my invention, the following is what I claim as new and desire to secure by Letters Patent:

The valve-block A and steam-channels C C' of the two balanced slide-valves D D, constructed, arranged, and operated substantially as and for the object specified.

JOHN H. WAIT.
